[57] CLAIM

The ornamental design for a support and reservoir assembly for a product dispenser, as shown and described.

DESCRIPTION

FIG. 1 is a perspective view of a support and reservoir assembly for a product dispenser showing our new design; FIG. 2 is a front view thereof;

FIG. 3 is a rear view therof with the broken lines showing a part of the dispenser for illustrative purposes only and forming no part of the illustrated design;

FIG. 4 is a right side view thereof, the left side view being a mirror image thereof with the broken lines showing a part of the dispenser for illustrative purposes only and forming no part of the illustrated design;

FIG. 5 is a top view thereof;

FIG. 6 is a bottom view thereof with the broken lines showing a part of the dispenser for illustrative purposes only and forming no part of the illustrated design; and,

FIG. 7 is a perspective view of the support and reservoir assembly for a product dispenser with broken lines showing a foot actuator and tubing for illustrative purposes only and forming no part of the illustrated design.
